HUGO GILLE, OF DUSSELDORF, GERMANY, ASSIGNOR TO FAÇONEISENWALZWERK L. MANNSTAEDT & CIE, AKTIENGESELLSCHAFT, OF KALK, NEAR COLOGNE, GERMANY.

REVERSING-VALVE FOR REGENERATIVE FURNACES.

1,033,577.

Specification of Letters Patent.

Patented July 23, 1912.

Application filed November 1, 1910. Serial No. 590,124.

To all whom it may concern:

Be it known that I, HUGO GILLE, a subject of the German Emperor, residing at Dusseldorf, in Germany, have invented certain new and useful Improvements in Reversing-Valves for Regenerative Furnaces, of which the following is a specification.

This invention relates to liquid-sealed reversing valves of the bell-type, which are raised, turned and lowered for the purpose of diverting, by means of a diametral partition, the currents of air and heating gases in regenerators.

The object of the invention is to provide a bell-valve of light construction, with a partition internally cooled by air and by the sealing liquid, and a device for preventing access of steam from the sealing trough to the interior of the bell when the valve is seated, and also improved mechanism for actuating the valve, with a view to securing smooth and easy movement, positively controlled throughout by the actuating device.

The invention is illustrated in the accompanying drawings, in which:

Figure 1 is a side view, partly in section, Fig. 2 a plan-view, with parts broken away, Fig. 3 a side-view, partly in section, showing a modification of the actuating gear, Fig. 4 a plan-view of this modified construction, and Fig. 5 is a plan-view of the sealing trough in which the valve is seated.

Like reference numerals denote like parts throughout the drawings.

The base 1 is a container comprising a circular trough and two transverse troughs 1^a and 1^b intersecting each other and forming a cross within the circle. The liquid in this container forms a seal for the bell 2, which has a pendent transverse partition 3 adapted to enter either of the transverse troughs 1^a, 1^b. For the purpose of forming this partition the bell is constructed with a depression producing a deep, diametral channel, open at both ends, with walls 3 and a floor 3^a. The partition is thus open to the atmosphere at the top and at both sides, and picks up sealing liquid each time it is dipped into one of the transverse troughs 1^a, 1^b. The partition and the liquid are thus efficiently cooled, and the bell can be made very light, which is an important advantage in regard to facility of actuation and of stoppage at the ends of the valve movements. The bell and partition make

steam-tight joints with frames 2^a which lie upon the container 1 and prevent the ascent of steam from said container into the bell, and the falling of soot into the trough.

The sector-shaped apertures 100, 200, 300, 400, bordered by the sealing trough are the ports at the ends of the conduits, the connections of which are to be reversed, that is to say, the connections are to be alternately:—100 to 200, 300 to 400, and 100 to 400, 200 to 300. The reversal is made by transferring the partition 3 from trough 1^a to trough 1^b, and vice versa. The partition can be lifted clear of the trough, and the bell turned, without removing the rim 70 of the bell from the circular trough.

The bell 2 is suspended from a support 11, by means of rods 12, the support being rotatable and vertically slidable on a post 13 rising from a beam 15 supported by pillars 16. The weight of the bell is balanced by a double-armed lever 22 which carries a weight 21 and engages a slideable collar 10 on which the support 11 rests. This collar is connected by rods 9 to a rider 8 working upon a screw 7. The gudgeons of this screw are mounted in bearings 17, and the screw can be driven by an electromotor 4 and toothed wheels 5 and 6. A cam-plate 14 with a slot 14^a projects from one side of the rider 8, and the slot is traversed by one of the rods 12. Two electric switches 18 connected to the motor 4 are carried by the beam 15 and have pendent switch levers 19 located in the path of an abutment 20 on 90 the rider 8.

The action of the apparatus described is as follows:—When the rider 8 is in either of its end positions on the screw 7, as for example in Fig. 1, the partition 3 of the bell is dipping into one or the other of the transverse troughs 1^a, 1^b, that is to say, the bell is lowered and is in one of its normal working positions. In order to reverse the valve, the motor 4 is started. This causes 95 the screw 7 to rotate and to traverse the rider 8, and the latter, acting through the rods 9 and collar 10 on the support 11, lifts the bell. During the lifting operation the rod 12 in the slot 14^a at first travels in a 100 straight part of said slot, but near the center of the traversing movement, when the partition 3 has been lifted clear of the frame 2^a, the bent part of the slot 14^a reaches this rod, and pushes the same outward, thus 105 110

causing the support 11, bell 2 to rotate through 45°. This rotation is completed when the bell has reached its highest position. Thereafter the continued traversing movement causes the bell to be lowered, and the slot 14^a pulls the rod 12 inward, thereby causing the bell to again rotate through 45° in the same direction as before, so that before the partition 3 has been lowered to the level of the frame 2^a the bell has been rotated through 90°. The result is that the partition enters the transverse trough perpendicular to that in which its edge was immersed prior to the lifting of the bell. 15 When the rider 8 arrives at the end of its travel, the abutment 20 actuates the switch lever 19 at that end, and thus stops the motor. For traversing in the opposite direction, and again reversing the valve, the motor is re-started, to rotate in the opposite 20 direction.

This arrangement may be modified by connecting the switches to an electrically actuated clutch and reversing gear, instead 25 of to the motor.

In the modification shown in Figs. 3 and 4 the rods 9 connect the collar 10 to a block 26 fixed to the central part of a plunger 23. The latter works at each end in a cylinder 30 24 communicating with a pipe 25. The block 26 is reciprocated by forcing fluid under pressure alternately into the cylinders 24, through the pipes 25. The cam-plate 14 is fixed to the block 26.

35 What I claim as my invention and desire to secure by Letters Patent of the United States is:—

1. A reversing valve for the purpose set forth comprising, in combination with a 40 seat consisting of an annular sealing trough and diametral sealing troughs, a bell having a partition produced by a diametral open ended depression of the bell-body, forming a channel which is open above and 45 at its ends and is adapted to enter said diametral troughs and receive water from and discharge the same into said troughs when lowered and raised respectively.

2. A reversing valve for the purpose set 50 forth comprising, in combination with a seat consisting of an annular sealing trough and diametral sealing troughs, a bell having a partition produced by a diametral open ended depression of the bell-body, forming a channel which is open above and 55 at its ends and is adapted to enter said diametral troughs, and frames adapted to make steam-tight joints between the bell and the trough-walls which are inside said 60 bell when the latter is lowered on to the seat.

3. A reversing valve for the purpose set 65 forth comprising, in combination with a seat consisting of an annular sealing trough and diametral sealing troughs, a bell hav-

ing a partition produced by a diametral depression of the bell-body, forming a channel which is open at its ends and is adapted to enter said diametral troughs, a vertically movable support carrying said bell, a horizontally movable traversing member, and means connecting said traversing member to said support so that the latter is first raised and then lowered during the movement of the traversing member from one 70 end of its travel to the other end. 75

4. A reversing valve for the purpose set forth comprising, in combination with a seat consisting of an annular sealing trough and diametral sealing troughs, a bell having a partition produced by a diametral depression of the bell-body, forming a channel which is open at its ends and is adapted to enter said diametral troughs, a vertically movable bell-support, a horizontally movable traversing member, means connecting said traversing member to said support so that the latter is first raised and then lowered during the movement of the traversing member from one end of its travel to the other, a rod connecting said support to the bell, and a plate fixed to the traversing member having a cam-slot through which said rod passes so that said plate imparts rotation to the bell during part of the traversing movement. 90 95

5. A reversing valve for the purpose set forth comprising, in combination with a seat consisting of an annular sealing trough and diametral sealing troughs, a bell having a partition produced by a diametral depression of the bell-body, forming a channel which is open at its ends and is adapted to enter said diametral troughs, a vertically movable bell-support, a horizontally movable traversing member, means connecting said traversing member to said support so that the latter is first raised and then lowered during the movement of the traversing member from one end of its travel to the other, a rod connecting said support to the bell, a plate fixed to the traversing member having a cam-slot through which said rod passes so that said plate imparts rotation to the bell during part of the traversing movement, and a counter-weight connected to said bell-support balancing the weight of the bell. 100 110

6. A reversing valve for the purpose set forth comprising, in combination with a seat consisting of an annular sealing trough and diametral sealing troughs, a bell having a partition produced by a diametral depression of the bell-body, forming a channel which is open at its ends and is adapted to enter said diametral troughs, a vertically movable bell-support, a horizontally movable traversing member, means connecting said traversing member to said support so that the latter is first raised and then low- 120 125 130

ered during the movement of the traversing member from one end of its travel to the other, a rod connecting said support to the bell, a plate fixed to the traversing member 5 having a cam-slot through which said rod passes so that said plate imparts rotation to the bell during part of the traversing movement, a motor actuating said traversing member, and motor-stopping devices located in the path of the traversing member

to be actuated by the latter at the ends of its travel.

In witness whereof I have signed this specification in the presence of two witnesses.

HUGO GILLE. [L.S.]
